UNITED STATES PATENT OFFICE.

AUGUST R. SCHOENKY, OF ST. LOUIS, MISSOURI, ASSIGNOR TO CHAMPION SHOE MACHINERY COMPANY, OF ST. LOUIS, MISSOURI, A CORPORATION OF MISSOURI.

WORK-FEEDING MECHANISM FOR SEWING-MACHINES.

1,032,303.

Specification of Letters Patent. Patented July 9, 1912.

Application filed July 11, 1911. Serial No. 638,026.

To all whom it may concern:

Be it known that I, AUGUST R. SCHOENKY, a citizen of the United States, residing at St. Louis, in the State of Missouri, have 5 invented a new and useful Work-Feeding Mechanism for Sewing-Machines, of which the following is a specification.

This invention relates to work feeding mechanism for sewing machines, and particularly for that class of sewing machines used for sewing soles on shoes.

One of the objects of this invention is to construct a work feeding mechanism which will be simple in construction, consist of a 15 few parts, and which will be accurate in its operation and adjustment eliminating all play; and to provide a construction in which the adjustment for stitches of different lengths can be made from practically 20 zero to a maximum.

Another object is to construct a mechanism which can be adjusted for alinement, etc., and in which such adjustment can be made exceedingly fine; and in which the 25 parts are so positioned and constructed that the adjustment can be made and the parts locked after adjustment from the front of the machine.

Further objects will appear from the 30 detail description taken in connection with the accompanying drawing in which:

Figure 1 is a fragmentary plan view of a sewing machine embodying this invention, parts being shown in section on the 35 line 1—1 Fig. 2. Fig. 2 is a fragmentary front elevation, and Fig. 3 is an enlarged section on the line 1—1 Fig. 2.

The machine to which this invention is applied is a sole sewing machine of the 40 type disclosed in Patent No. 473,870, and more particularly such as shown and described in application Serial No. 631,290, and similar parts are designated by the same reference characters as in said application.

In the drawings, 26 designates a head or base for supporting the various parts. This base supports a pair of brackets, one of which is shown at 29, which brackets are provided 50 with bearings for a main driving shaft having mounted thereon a number of cams, one of which is shown at C and provided with a cam groove c^s . The head 26 supports and has formed integral therewith a forwardly extending lug 34 forming a support

for the work feeding mechanism. A casting 35 supports the needle segment 51 and its needle 52, and also the work support or table 129. A bracket 40 is bolted to the head 26 and is provided with a forwardly 60 extending arm 43 forming a bearing for the feed slide actuating lever.

The above construction is described in detail in the application referred to.

The forwardly extending lug 34 forms a 65 guide 100 for a feed slide 101. This feed slide carries a post 102 forming an adjustable support for the awl and its carrier or segment. The awl 103 is clamped in the awl segment 104 which is loosely mounted 70 for oscillating movement upon a stub shaft in the upper end of the post.

An actuating lever is pivoted upon a shaft 107 mounted in the arm 43, and one arm 108 of this lever is provided with a cam roll 109 engaging the cam groove c^s , while the other arm 110 is provided with a guideway 111. A link 112 is pivotally connected to the post 102 by a pivot bolt 112^a and is provided at its other end with 80 a block 113 engaging the guideway 111. The guideway 111 is cut on the arc of a circle having the pivot 112^a as its center so as to prevent shifting of the awl out of alinement with the needle when the block 85 113 is adjusted in the guideway. The guideway 111 is cut in the lower face of the arm 110, and the upper face of the link therefore bears against the lower face of the arm. An arm 114 is secured to and 90 preferably formed integral with the link 112 and is spaced therefrom so as to extend over the upper face of the arm 110, and forms a handle by means of which the block 113 may be shifted in the guideway. 95 This arm is displaced with respect to the link so that the block may be moved to the pivot of the actuating lever. This construction is advantageous, since it permits the feed of the work to be adjusted from practically zero to a maximum. If the arm 114 were in alinement with the link, then it would be impossible to move the block 100 near the center of the actuating lever, since the edge of the arm would engage the pivotal support or bearing for the actuating lever before the block would reach the pivot. However by displacing the arm with respect to the link, this block can be moved up to the very center of the lever 110

so that the feed can be adjusted to practically zero. The link 112 and the arm connected thereto embrace the lever so as to form a snug fit, and the upper face of the lever is provided with a plurality of holes 115 adapted to receive stop pins 115^a for locating the arm 114 and the link to which it is connected.

The pivot bolt 112^a passes through a cylindrical block 116 which is mounted for sliding movement in the post 102 and the link is locked on the pivot by means of lock nuts 117. The cylindrical block is provided with a vertical groove or guideway 118 with which cooperates the pin 119 of an eccentric 120 rotatably mounted in the post 102. A part of the eccentric shank is threaded at 121 and the post is correspondingly tapped to secure the eccentric in position in the post. The eccentric is provided with a hexagonal head 122 so that it may be engaged by a wrench and be turned. The eccentric is bored axially to receive a locking pin 123 which is threaded at 124 into the eccentric and is provided with an angular head 125 adapted to be engaged by a wrench. The block may be adjusted in the post by turning the eccentric, and may be locked in position by means of the locking pin 123, this locking pin engaging the bottom of the guideway in the block so as to firmly clamp the eccentric and the block in adjusted position in their bearing in the post. By means of this construction the awl may be adjusted to aline it with the needle, and in view of the eccentric connection this adjustment can be made exceedingly accurate and fine.

It will thus be seen that this invention provides a work feeding mechanism which will be accurate in its operation and in its adjustment. Since the link and the handle connected thereto embrace the actuating lever, the link will be maintained in engagement without auxiliary retaining means. The heads 122 and 125 extend to the front of the machine so as to be readily accessible from the front of the machine, which is advantageous in view of the fact that it would be difficult to operate adjusting means if such adjusting means were positioned among the crowded mechanism adjacent the feed slide. The eccentric as well as the block are constructed so as to be readily removable from the post.

It is obvious that various changes may be made in the details of construction without departing from this invention, and it is therefore to be understood that this invention is not to be limited to the specific construction shown and described.

Having thus described the invention what is claimed is:

1. In a sewing machine, the combination with a feed slide and an actuating lever

having a guideway therein, of a link connected to said slide and having a block adjustable in said guideway, parts of said link extending under and over said lever to embrace the same, and adjustable stops on said lever engaged by a part of said link. 70

2. In a sewing machine, the combination of a feed slide, an actuating lever therefor, a link connecting said slide and lever and extending under the lever, and a handle on said link extending over the lever, whereby said lever is embraced by said link and said handle. 75

3. In a sewing machine, the combination with a feed slide and an actuating lever 80 therefor, of a link connected to said slide and having an adjustable connection with said lever, said link having a part thereof extending under said lever, and a handle on said link extending over said lever, 85 whereby said lever is embraced by said link and said handle, said handle being displaced laterally with respect to said link to permit the link to be moved to the pivot of said lever. 90

4. In a sewing machine, the combination with a feed slide and an actuating lever having a guideway therein, of means above said lever for pivotally supporting the same, a link connected to said slide and 95 having a block engaging said guideway, said link extending underneath said lever, and a handle on said link extending over said lever and having the part thereof facing said lever supporting means displaced laterally with respect to said link. 100

5. In a sewing machine, the combination with a needle, an awl, and an awl slide, of an actuator for said awl slide, a connection between said actuator and awl slide including an eccentric shaft mounted on said slide and rotatable thereon to aline the awl with the needle, said shaft being positioned transversely of the line of movement of said slide and having a forwardly extending operating head thereon. 105 110

6. In a sewing machine, the combination with a needle, an awl, and an awl slide, of an actuator for said awl slide, an eccentric shaft mounted on said slide, and a link connected to said actuator and to said shaft, said shaft being adjustable to aline the awl with the needle. 115

7. In a sewing machine, the combination with a needle, an awl, and an awl slide having a post for supporting said awl, of an actuator for said awl slide, a forwardly extending adjustable shaft mounted in said post, means connecting said actuator and said shaft constructed to cause said shaft to aline the awl with the needle, and an operating head on the forward end of said shaft. 120 125

8. In a sewing machine, the combination with a feed slide having an awl, and an ac- 130

tuator for said slide, of a connection between said actuator and said slide including a block slidably mounted in said slide, and an eccentric adjustably mounted in said slide and connected with said block.

9. In a sewing machine, the combination of a feed slide, an actuator therefor, and a connection between said slide and actuator including a block, an adjustable eccentric engaging said block, and a locking pin extending through said eccentric and engaging said block.

10. In a sewing machine, the combination of a feed slide, an actuator therefor, and a connection between said slide and actuator including a block adjustable in said slide, an adjustable eccentric screwed in said slide and engaging said block, and a locking pin screwed into said eccentric and engaging said block.

11. In a sewing machine, the combination of a feed slide having a post thereon, an actuator for said slide, a connection between said actuator and slide including a block 25 slidable in said post, and an adjustable eccentric in said post and engaging said block.

12. In a sewing machine, the combination

of a feed slide having a post thereon, an actuator for said slide, a connection between said actuator and slide including a block 30 slidable in said post, an adjustable eccentric in said post and engaging said block, and a locking pin extending through said eccentric engaging said block.

13. In a sewing machine, the combination 35 of a feed slide, an actuator therefor, and a connection between said slide and actuator including an adjustable eccentric, and a pin extending through said eccentric and constructed to lock it in adjusted position. 40

14. In a sewing machine, the combination of a feed slide, an actuator therefor, and a connection between said slide and actuator including an adjustable shaft mounted in said slide and extending forwardly, and a 45 pin extending through said shaft and constructed to lock said shaft in adjusted positions.

In testimony whereof I affix my signature in presence of two witnesses.

AUGUST R. SCHOENKY.
